UNITED STATES PATENT OFFICE

150,198

DESIGN FOR A DIVING BELL

Ross H. Bird, Houston, Tex.

Application July 26, 1946, Serial No. 132,003

Term of patent 14 years

(Cl. D71—1)

To all whom it may concern:

Be it known that I, Ross H. Bird, a citizen of the United States, residing at Houston, in the county of Harris and State of Texas, have invented a new, original, and ornamental Design for a Diving Bell, of which the following is a specification, reference being made to the accompanying drawings, forming part thereof.

Fig. 1 is a perspective view of a diving bell showing the new design; and

Fig. 2 is a plan view thereof.

I claim:

The ornamental design for a diving bell, substantially as shown.

ROSS H. BIRD.
